(57) **CLAIM**

The ornamental design for a beverage asset tracking device, as shown and described.

DESCRIPTION

FIG. 1 is a perspective view of a beverage asset tracking device according to my new design;

FIG. 2 is a top view of the beverage asset tracking device of FIG. 1;

FIG. 3 is a bottom view of the beverage asset tracking device of FIG. 1;

FIG. 4 is a first side view of the beverage asset tracking device of FIG. 1;

FIG. 5 is a second side view of the beverage asset tracking device of FIG. 1;

FIG. 6 is a front view of the beverage asset tracking device of FIG. 1; and,

FIG. 7 is a back view of the beverage asset tracking device of FIG. 1.

The broken lines illustrate portions of the beverage asset tracking device and form no part of the claimed design.
